INVENTOR

EMANUEL W. HARTMAN

By Clarence E. Walker

ATTORNEY

UNITED STATES PATENT OFFICE.

EMANUEL W. HARTMAN, OF MIAMI, FLORIDA.

SHALE-DISTILLING APPARATUS.

Application filed September 6, 1921. Serial No. 498,788.

To all whom it may concern:

Be it known that I, EMANUEL W. HARTMAN, a citizen of the United States, residing at Miami, in the county of Dade and State 5 of Florida, have invented certain new and useful Improvements in Shale-Distilling Apparatus, of which the following is a specification.

This invention relates to an improvement 10 in shale handling apparatus and more particularly to an apparatus having a retort in which the shale is distilled.

One object of this invention is to provide in such apparatus a retort having a cylindrical chamber provided with a series of shelves or decks over which the shale is moved by means of a series of rotating conveyors and in which retort the individual shelves are heated directly so that the temperature under which the shale on each shelf is treated can be controlled.

Another object of this invention is to provide in the retort of this apparatus a rotatable shaft which is normally supported 25 on bearings beneath its foot but which may be raised under the action of the shale during the operation of the apparatus without disturbing its driving connection.

A further object of this invention is to 30 provide in the retort a corrugated base plate so that any distortion of the plate due to the extreme heat to which it is subjected during the distillation operation will be taken up by such corrugations without interfering in any way with the operation of the vertical driving shaft.

A still further object of this invention 35 consists in providing in each of the shelves of the retort a plurality of heating elements preferably electrically controlled.

Other objects will appear from the following description of the invention taken in connection with the drawings which form a part thereof and in which

45 Fig. 1 is a longitudinal sectional view of the retort forming a part of the apparatus of this invention;

Fig. 2 is a side elevation of the retort showing the driving connections;

50 Fig. 3 is a plan view of the base plate of the retort;

Fig. 4 is a cross section of such plate, taken on the line 5—5 of Fig. 3;

Fig. 5 is a plan view of one of the shelves

or decks intended to be used with the retort;

Fig. 6 is a cross section of the deck taken on the line 7—7 of Fig. 5;

Fig. 7 is a plan view of one of the conveyors by which the shale is moved over the shelves;

Fig. 8 is a cross section taken on the line 9—9 of Fig. 7;

Fig. 9 is a cross section taken on the line 10—10 of Fig. 1 and showing the bearings 65 on which the driving shaft is supported;

Fig. 10 is a side view of one of the traps intended to be used with the retort with one side plate removed; and

Fig. 11 is a diagrammatic view showing 70 the course of travel followed by the shale through the retort.

Referring to the drawings the reference numeral 20 is used to indicate the retort. The retort 20 is formed by the assemblage 75 of the base plate 22, the decks 23 and the cover 24. These elements are all circular and are encased by the brick walls which are raised on the foundation 25 after these parts are assembled in order to prevent as 80 much as possible any waste of heat. Mounted on suitable supports in the base of the retort is a vertical squared shaft 26 which carries a series of conveyors 27, one conveyor being provided for each deck. On 85 the cover 24 of the conveyor is mounted a trap 28 through which shale is supplied to the retort while a second trap 29 is mounted below the retort and connected therewith by means of a chute 30 to receive and discharge the waste shale from the retort. A central opening 31 is provided around the shaft 26 in the cover 24. Mounted on the cover with its edges enclosing the opening 95 31 is a dome 32 from one side of which leads a pipe line 33.

The base plate 22 shown in detail in Figs. 3 and 4 is provided with a series of concentric corrugations 34. During the distillation operation this plate is subjected to 10 very extreme heat and it has been found that if the plate is flat its tendency to expand under the extreme heat will cause it to interfere with the operation of the drive shaft 26. For that reason the plate is made corrugated so that any change in the dimensions of the plate will be taken up by the corrugations. Through the plate 22 is

formed an opening 35 leading to the chute 30 referred to above. Around the periphery of the plate 22 are provided pairs of projecting fingers 36 for the purpose to 5 be described later.

In the present embodiment of this invention the decks 23, eight in number, are mounted upon the plate 22. These decks are identical in construction and as an example one is shown in Figs. 5 and 6 of the drawing. Referring to these figures it will be noted that the deck consists of a flat plate 37 having a downwardly extending peripheral flange 38 and having a central 10 opening 39. Around the opening 39 is provided an annular flange 40 for a reason to be given later. From the upper and lower edges of the flange 38 project the annular flanges 41 and 42, both of which 15 are provided with a series of fingers 43 which correspond in every respect to the projecting fingers 36 of the bottom plate.

Embedded in the plate 37 are a series of heating elements 44, here shown as electrically controlled. Certain only of the wires from the electric elements are shown in Fig. 1 projecting through the brick wall of the retort. It is understood, however, that all the wires from all the elements may be 20 brought through the wall so that the heating elements may all be easily controlled.

In each of the decks 23 is provided an opening 45 by which the shale carried on one deck is led to the deck below. Inasmuch 25 as these decks are made identical it is obvious that the various openings 45 therethrough must be so located with respect to the decks above and below that they are out of alignment with the openings in such decks.

The conveyor plates 27 mounted on the shaft 26 are shown in detail in Figs. 7 and 8. These plates are provided with an annular 45 series of bottomless pockets 46. It will be observed that the inner dimensions of these pockets are slightly less than the dimensions of the openings 45 and 35. The conveyor plate 27, with its pockets 46, is rotated from the shaft 26 by means of a collar 47 having a squared inner surface and connected to the inner ring 48 by means of the straps 49. The conveyors 27 are nine in number, one being provided for each deck and one for the base plate 22. The collars 47 of these 50 conveyors rest one upon the other and are made of the exact size so that the conveyors rotate a certain distance above the base plate 22 or shelf 23, with the plates 50 forming the pockets 46 located a trifle above the 55 upper surface of the decks 23.

The driving shaft 26 has at its lower end a tongue 51 which rests in a slot 52 provided at the upper end of a short shaft 53. In the operation of the apparatus there is a 60 tendency to raise the drive shaft 26 as the

supply of shale in the retort increases so that eventually all the weight of the shaft is removed from the bearings 58 and is carried by the shale on the various decks. In order to permit this raising of the shaft without any disturbance of the bearings the tongue and slot connection indicated at 51 and 52 is provided. The shaft 53 is squared at its lower end 54 to seat within the pocket 55 provided in the plate 56. The plate 56 rests upon an anti-friction surface which comprises the roller bearings 58 between circular plates 57. The roller bearings 58 as shown particularly in Fig. 9 comprise the inner ring 59 and the outer ring 60 connected by a series of bolts 61 on which rotate freely the individual disks 62 which support the entire weight of the shaft. The portion of this shaft below the walls 25 of the retort is enclosed within a cylindrical casing 63 which is made up of two parts, the lower part 64 in which the bearings rest being provided with any suitable means 65 for supplying lubricant to the bearings.

Resting upon the uppermost conveyor 27 is a flanged collar 66 which in turn supports the flanged sleeve 67 which extends through the dome 32 above referred to. In order to prevent the escape of any of the products of distillation between the sleeve 67 and the dome 32 a suitable packing ring 68 is provided. On the upper end of the shaft 26 is mounted the pulley 69 by which the shaft is rotated.

The feed trap 28 comprises a casing 70 having a cylindrical chamber through which extends the shaft 71. On the shaft 71 is mounted a series of arms 72 which receive the material fed into the chamber thru the hopper 73 and carry it to the opening 74 through which it is discharged into the retort. The discharge trap 29 is made similar in every respect to the feed trap 28 and will not therefore be shown nor described in detail. Below the trap 29 is provided a chute 75 into which falls the waste shale discharged from the trap 29. Mounted on the shaft 71 of the feed trap 28 is a pulley 76 by which the shaft 71 is driven. Connected to the shaft 71 beyond the pulley 76 by means of a union 77 is a shaft 78 suitably supported in a bracket 79 carried on the foundation of the retort. At the outer end of the shaft 78 beyond the bracket 79 is provided a pulley 80 which is located directly above the pulley 81 mounted on the shaft 82 of the discharge trap 29. A supplementary support for the shaft 82 in the form of a bracket 83 is provided.

Referring particularly to Fig. 5 of the drawing and to the diagrammatic showing Fig. 11, it will be observed that the various openings 45 in the decks 23 are mounted out of alignment with each other. For convenience in description the several decks will be

referred to as 23^A to 23^H inclusive, the first number indicating the upper deck and the last number the lower deck. The same system of numbers will be used with reference 5 to the openings 45 in each deck. The opening 35 in the bottom plate 22 is also shown.

When the retort is in operation the conveyors 27 are rotated in the direction of the arrow 84 in Fig. 5 and the shale fed from 10 the feed trap 28 drops onto the upper deck 23^A at the point 85 which, it is observed, is directly above the discharge opening 35 in the base plate 22. The shale is carried around over the deck by the first or top conveyor 15 to the opening 45^A through which it drops to the second deck 23^B. It is then picked up by the second conveyor and carried around the deck 23^B to the opening 45^B indicated in dotted lines on Fig. 6 through 20 which it drops to the third deck 23^C. The further progress of the shale through the machine over the decks 23—D—E—F—G—H— and through the openings 45^C to 45^H to the base plate 22 can be easily traced in the diagram 25 shown in Fig. 11. When reaching the base plate 22 the shale is carried by the lowest conveyor 27 to the opening 35 and thence through the chute 30 to the discharge trap 29 and out through the chute 75.

As pointed out above the openings 45 and 30 35 are slightly larger than the pockets 46 of the conveyors 27 so that as each pocket passes over the deck opening the entire charge falls through the opening into the 35 pocket of the conveyor below, this second pocket being empty because the charge therein had just been dropped through the opening 45 over which it had just passed.

If it is desired for any reason to increase 40 the number of decks this can be done without in any way interfering with the operation of the machine, it being understood, however, that if the number of decks is increased the arrangement shown in Fig. 5 will be slightly 45 changed so as to increase the number of openings provided in a single circle or else the arrangement shown in Fig. 5 will be retained and the machine arranged so that the discharge opening 35 is at the proper relation 50 to the opening in the lower deck.

The flanges 40 on each deck overlap to 55 slightly the inner wall of the pockets 46 to prevent the shale from falling through the openings 39. A flanged ring 86 is mounted 60 at the bottom of the squared portion of the drive shaft and extends into the inner corrugation 34 on the plate 22 to prevent any shale from working down around the shafts 26 and 53 into the bearings 58.

The base plate 22 has a central opening 87 made larger than the shafts 26 and 53 which extend through it. Around this opening 65 the plate 22 is thicker than elsewhere and rests in a pocket 88 of the foundation 25.

Below the plate 22 is provided an annular

chamber 89 which may be heated in any suitable way if desired, such as for example by means of gas burners as shown in my co-pending application, Serial No. 478,140 filed 70 June 16, 1921.

In order to prevent the escape of the products of distillation between the cover 24, decks 23 and base plate 22 the peripheries of these members are interlocked. On the upper face of the plate 22 and the upper 75 faces of the flanges 41 of the decks 23 are provided annular ridges 90 which seat in annular grooves 91 in the flanges 42 of the decks above. The cover 24 is similar in construction to the decks 23, being provided 80 with a depending flange 92 at the top and bottom of which are annular flanges 93 and 94. In the flange 94 is provided an annular groove 95 to receive the ridge 90 on the upper deck. The flange 93 is shorter than the 85 flange 94 and merely contacts with the wall without being embedded therein. On the flange 94 are pairs of projecting fingers 96 which correspond to the fingers 36 and 43 referred to above. The plate 22, decks 23 90 and cover 24 are clamped together by means of bolts 97 engaging the projecting fingers of the adjacent members. By reason of the annular ridges and grooves and the clamping bolts, the joints between the peripheries 95 of the plate, decks and cover are thus tightly sealed.

The moving parts of the retort are actuated by any prime mover which through 100 suitable gearing drives the chains 98 and 99. The chain 98 passes around the pulley 69 and rotates the drive shaft while the chain 99 passes around the pulley 76 and drives the traps 28 and 29 by the connecting 105 means shown in Figs. 1 and 2.

The vertical shaft 26 has a central core 100 in which is placed a thermometer 101 which indicates on the dial 102 the temperature of the retort. If this rises above a certain predetermined amount the electric bell 110 103 is energized by any suitable temperature-controlled means, a thermocouple for example to give warning.

It will be noted that by the use of the 115 arms 48 in the conveyors 27 an open passage 104 is provided at the center of the retort. Through this passage the products of distillation are guided into the dome 32 and thence to the pipe line 33 which is made up of a plurality of pipe sections secured together and leads into a cooling chamber (not shown). A fan 118 is connected to the pipe line 33 to create suction and increase 120 the speed of travel of the products of distillation.

While certain specific embodiments have been shown and described applicant is not to be limited thereby since it is obvious that other embodiments may be made without departing from the spirit and scope of this 130

invention as set forth in the following claims.

Having thus described my invention that which I claim as new and for which I desire the protection of Letters Patent of the United States is the following:

1. A retort for a shale distilling apparatus comprising a plurality of vertically spaced annular shelves over which the shale being distilled travels during the operation of the apparatus, a plurality of conveyors for moving the shale, a central vertical shaft by which said conveyors are actuated, the shaft extending through the central openings in said annular shelves so that the shaft and shelves define an annular space into which the products of distillation pass and a dome at the top of said retort over said annular space in which said products collect.
2. The combination with a retort of the type set forth in claim 1 of a pipe line leading from said dome for carrying off said products of distillation and a blower adapted to force air into said pipe line and thus create suction to further the collecting of said products.
3. In the retort of a shale distilling apparatus, a plurality of shelves for the shale being distilled, conveyors for moving the shale over said shelves, positively driven vertically movable means for actuating said conveyors, a support including anti-friction means for said actuating means, and a tongue and slot connection below said shelves and above said anti-friction means to permit separation between said shelves and said conveyors without disturbing the connection between the actuating means and its support.

4. In the retort of a shale distilling apparatus, a plurality of shelves for the shale being distilled, a plurality of conveyors for moving the shale over said shelves, a positively driven vertically movable shaft for actuating said conveyors, a support for said shaft, and a tongue and slot connection below said shelves and between said shaft and said support.

5. In the retort of a shale distilling apparatus, a plurality of shelves for the shale being distilled, a plurality of conveyors for moving the shale over said shelves, a positively driven vertical shaft terminating below said shelves for actuating said conveyors, a second shaft below said first shaft and connected thereto by tongue and slot mechanism and anti-friction bearings on which said second shaft rests.

6. In the retort of a shale distilling apparatus, conveyors for moving the shale being distilled, a positively driven vertical shaft terminating below said shelves for actuating said conveyors, a second shaft coaxial with and below said first shaft, and a tongue and slot connection between said shafts to permit a certain axial separation of said shafts.

7. In a shale distilling apparatus, a retort having a cylindrical distilling chamber, a plurality of shelves around the walls of said chamber, a corrugated base plate in said chamber having a central hole therethrough, conveyors passing over said shelves and base plate for moving the shale thereon and a vertical shaft for actuating said conveyors at the center of said chamber and passing through the hole in said base plate.

In testimony whereof I affix my signature.
EMANUEL W. HARTMAN.
